HEADLEY TOWNSEND BACKHOUSE, OF LONDON, ENGLAND.

SHEET-FEEDING DEVICE.

Application filed February 28, 1924, Serial No. 695,865, and in Great Britain April 10, 1923.

This invention consists in improvements in or relating to sheet-feeding apparatus for printing machines and other machines operating on paper or like sheets.

5 The main application of the invention is to apparatus for feeding sheets one at a time to the registering devices of the printing press or other machine in conjunction with which the apparatus is employed. In 10 such apparatus each sheet in succession is conveyed (for example by endless bands) to a position in which the leading edge of the sheet is arrested by two or more registering stops usually termed the front "lays" or "lay 15 marks". The front lays insure that each sheet is brought into the same position, as regards the alignment of its forward edge, before being passed on to the printing or like machine.

20 It is desirable, particularly with modern requirements of high-speed output from sheet-feeding apparatus, that the initial travel of the sheet from the sheet pile towards the front lays should be comparatively rapid but that the sheet should be slowed up immediately before it reaches the front lays so that it will not rebound therefrom. The present invention is concerned with means for controlling the speed at 25 30 which the sheets are conveyed by the feeding apparatus so that the above requirements will be fulfilled.

This invention provides in combination with sheet-feeding apparatus for a printing 35 press or other machine operating on paper or like sheets, variable speed driving mechanism for the sheet-feeding means, comprising two cranks or equivalent devices of unequal lengths, one constituting the driving 40 member and the other the driven member of the mechanism, said cranks being rotatable about parallel axes located as specified hereunder and being coupled by a pin, stud or other projection from the smaller crank in 45 engagement with a radially or substantially radially directed slot or guide in or on the larger crank.

The location of the axes of the two cranks is such that the circle of revolution of the 50 smaller crank, when projected on to the plane of rotation of the larger crank, will lie within the circle of revolution of said larger crank. This arrangement insures that during the rotation of the cranks about their 55 respective axes, one being rotated by the

other, the pin on the smaller crank will at all times remain in engagement with the guide on the larger crank. Variable speed mechanism of this general type has hitherto been proposed for purposes other than that 60 with which the present invention is concerned, and no claim is made herein to this mechanism per se.

In one form of the present invention each of the two cranks aforesaid is constituted 65 by a disc carrying at its periphery, or having its periphery formed as, a toothed ring for the transmission of the drive to and from the mechanism.

One example of this invention will now 70 be described with reference to the accompanying drawings, in which—

Figure 1 is a cross-section through a variable speed gear-box embodying the invention; 75

Figures 2 and 3 are diagrams illustrating the operation of the mechanism;

Figure 4 is a similar diagram showing a modification in the disposition of the guide on the larger crank; 80

Figure 5 is a diagram similar to Figure 4 and illustrating a possible modification in the shape of the guide.

Like reference numerals indicate like parts in the various figures. 85

The arrangement shown in Figures 1, 2 and 3 will first be described. The two cranks are constituted by disc members 10 and 11, the former corresponding to the larger crank and the latter to the smaller crank. The 90 discs 10 and 11 are formed integrally with or are secured to shafts 12 and 13 which are mounted for rotation in bearings 14, 15 carried in a gear-box or housing 16. The two discs 10, 11 are unequal in diameter and are mounted face to face with their axes of rotation parallel. The discs are so placed that there is one point in the periphery of each at which the edges of the discs are in line with each other—that is, considered in 95 a direction along the axes of the discs. In Figure 1 the position of alignment is at the right-hand side of the discs. Secured to the smaller disc 11 near the periphery thereof is a stud 17 which extends towards the disc 10 in a direction parallel with the axis thereof. Cut substantially radially across the face of the disc 10 is a slot 18 within which engages the outer end of the stud 17. This 100 end of the stud is fitted with an anti-friction 105 bearing. The slot 18 is of a width such that it will 110

roller 19 of such size that a slight clearance is left between the periphery of the roller and the side walls of the slot.

The disc 10 is formed with a bevel gear 20 which meshes with a co-operating gear-wheel 21 carried by a shaft 22, constituting the main driving or input shaft of the mechanism. The disc 11 is driven by the pin-and-slot connection aforesaid from the disc 10. 10 Rotation of the disc 11 is transmitted to a sleeve 25 through meshing gears 23 and 24 formed respectively on the rim of the disc 11 and on the sleeve. From the sleeve 25 the drive passes through meshing gears 26 and 15 27 to a shaft 28 which constitutes the driven or output shaft of the mechanism.

In operation the shaft 22, and therefore also the disc 10, is driven at constant angular speed. When the discs are in the position 20 shown in Figure 2 the stud 17 is at the limit of its travel towards one end of the slot 18. When in this position the part of the slot 18 which engages the roller 19, that is the part of the disc 10 which transmits motion to 25 the disc 11 is at a maximum operative distance from the centre of rotation of the disc 10 and is therefore rotating at a maximum peripheral speed. Under these conditions the angular speed of the smaller disc 11 and 30 therefore of the output shaft 28 is a maximum. When the disk 10 has moved through a portion of a revolution the slot 18 and the stud 17 assume the position shown in Figure 3. As will be seen the roller 19 has shifted 35 radially inwards along the slot and the peripheral speed of the driving portion of the disc 10 has now been considerably reduced. The angular velocity imparted to the disc 11 and therefore to the output shaft, is consequently also reduced. It is at this period 40 that the slowing up of the sheet-feeding means takes place.

Various modifications may be made in the 45 shape and disposition of the slot in the disc member 10 in order to vary the rate at which the speed of the final drive changes. The disposition of the slot is not necessarily strictly radial although it will always be in a general direction from the periphery towards the centre about which the disc 10 rotates. For example the slot could be located 50 slightly to one side of the centre as shown in Figure 4, or again the slot may be curved at its ends as illustrated in Figure 5.

It is to be understood that the direction in 55 which the drive is transmitted through the mechanism may be reversed, that is to say, the shaft 28 may be the driving member and the shaft 22 the driven member. Under these 60 conditions the smaller disc is rotated at constant angular velocity and the variable speed is obtained from the larger disc. In place of the disc members described herein cranks or equivalent devices may obviously be employed. Again instead of a slot cut in the 65 face of the disc 10 the latter may be formed with upstanding ribs constituting a guide to engage the roller 19.

I claim:—

1. The combination with sheet feeding apparatus of the band-conveyor type of variable speed driving mechanism for the conveyor bands, said mechanism comprising in combination two disc-members unequal in diameter and mounted face to face for rotation about parallel axes, one disc-member constituting the drive and the other the driven member of the mechanism, a slot extending across the face of the larger disc and having a central straight diametral portion and end portions which are curved to one side of the central portion in opposite directions at opposite ends respectively of said slot, and a projection extending from the smaller disc into engagement with the slot aforesaid, the distance between the axes of the two discs being such that the projection will remain in engagement with the slot in all angular positions of both discs. 70 75 80 85

2. Variable speed driving mechanism for sheet-feeding apparatus comprising in combination two discs unequal in diameter and mounted face to face for rotation about parallel axes, one disc constituting the driving member and the other the driven member of the mechanism, a substantially diametral slot in the face of the larger disc, a projection extending from the face of the smaller disc into engagement with the slot aforesaid, and a toothed gear member carried at the periphery of each of the discs, the distance between the axes of the two discs being such that the projection will remain in engagement with the slot in all angular positions of both discs. 90 95 100 105

In testimony whereof I affix my signature.

HEADLEY TOWNSEND BACKHOUSE.
